METHOD FOR FORMING FUR FILLED YARN

Frances Sonin and Morris H. Siegel,
New York, N. Y.

Application October 11, 1943, Serial No. 505,716

18 Claims. (Cl. 57—164)

1
The invention relates to a method and apparatus for forming filled or core yarn to be woven into a fur filled fabric in making artificial fur from which may be fashioned coats and other articles usually made from natural fur.

The primary object of the invention is to utilize and thus provide a new market for a presently cheap form of waste fur hairs which, due primarily to the extremely short length of most of the hairs, are of no practical use and can thus be purchased cheaply from the fur industry. This waste comes from clipping, cutting, shavings, combings and dyeing in the treatment of fur skins and exists as an indefinite fluffy mass of entangled hairs of varying lengths but mostly of short lengths. This waste material is at present being thrown away by the furriers as a useless by-product of their work. The present disclosure contemplates the forming of an end product from this waste material and which end product is a woven fabric which will have most of the visual characteristics of the fur side of a natural skin.

In actual practice, it has been found possible to mix the hair from different kinds of animal skins in practicing the method herein featured and in this way to give a wide variety of novel and beautiful effects to the resulting fabrics not known with the natural skins.

Considering the method aspect of the present disclosure, the object is to provide an improved technique for utilizing the fur waste as a coating for a thread or similar filament to form a fur filled yarn capable of being used conventionally in a fabric weaving machine. The method particularly contemplates the forming of the yarn by a sequence of steps including a disintegrating and opening out of the mass of indefinitely intermeshed hairs in which this waste is available; the prelaying of the hairs at least somewhat in parallelism; a gentle lifting of the hairs on to a travelling thread, in distinction from blowing them on to the thread, and which thread is preferably rotating about its own axis and sometimes coated with an adhesive.

Various other objects and advantages of the invention will be in part obvious from a consideration of the method features of the disclosure and from an inspection of the accompanying drawing and in part will be more fully set forth in the following particular description of one method of practicing the invention, and the invention also consists in certain new and novel modifications of the preferred method and other features of construction and combination of parts hereinafter set forth and claimed.

2
In the accompanying drawing:

Fig. 1 is a plan view of a machine forming a preferred embodiment of the apparatus aspect of the disclosure with parts shown largely in symbolic outline, with the contents of the hopper at the left side of Fig. 2 omitted, and which machine in its operation discloses one way in which the method aspects of the invention may be practiced; in this showing the driving mechanism for actuating the several movable parts have been omitted to avoid confusion of showing conventional drive mechanism;

Fig. 2 is a vertical sectional view taken in the medial longitudinal plane through Fig. 1;

Fig. 3 is an enlarged plan view of the top of the treating compartment at the upper right hand portion of Fig. 2 showing the parallel relation of the core forming thread to the discharge slot;

Fig. 4 is an enlarged detail view in axial section of the ironer shown in smaller form in advance of the slot in Figs. 1 and 2;

Fig. 5 is a view of a short length of the finished yarn as it comes off the machine, highly magnified in an attempt to show its details and shown partly in longitudinal section; and

Fig. 6 is a transverse sectional view of the yarn shown in Fig. 5 taken on the plane indicated by the line 6—6 of Fig. 5.

30 The machine 10 may be divided for purposes of description into a measuring device 11, a combined disintegrating and hair applying device 12 and an organization 13 of thread treating elements.

35 The measuring device 11 comprising an open top hopper 14 provided in an inside wall and midheight thereof with a discharge port 15. Positioned in order from left to right in the hopper is a feeder 16 and a measuring drum 17 for receiving the waste from the feeder. Between the drum 17 and the port 15 is a stripper 18 for flipping a layer of waste off the drum, through port 15 and thus into the first or receiving compartment 19 of the device 12.

40 The feeder 16 comprises a broad bladed upstanding pusher plate 20 slidably mounted for reciprocatory movement along the inclined outer side 21 of the hopper 14. The pusher is hung from a lever 22 so as to swing therefrom and the lever is operatively connected to the drive mechanism of the machine (not shown) to operate with sufficient activity to maintain the fur waste against the measuring drum 17 as it is introduced into the hopper. The pusher in its elevating movement permits the waste to fall between itself

and the drum 17 and in its lowering movement packs the waste against the perimeter of the drum.

The measuring drum is a metal wheel mounted to be driven from shaft 23 connected to the main driving mechanism. The periphery of the drum is a narrow band 24 in one form of the drive about one and one-half inches wide and provided with a plurality of circumferentially spaced apart short ledges 25 extending transversely of the band 24. Each ledge is provided at its outer edge with a flange 25'. All of the flanges extend in the direction of rotation of the drum, that is in a clockwise direction. A doctor 26, provided with outwardly projecting wire spring fingers 26' is mounted for rotation above the drum to feed the material thereto.

The flanged ledges 25 on the drum act as the drum rotates from left to right about its top to coat with the doctor to withdraw from the mass of hair in the hopper a measured amount of the mass per rotation of the drum and doctor and draws it out into a long, thin ribbon-like form having the width of the drum. The ledges are very small extending beyond the drum about $\frac{1}{2}$ of an inch so that the resulting ribbon of matted hair has about that thickness as it leaves the drum. As the drum rotates it advances this ribbon over the top of the drum, past the stripper 18 and as a freely floating streamer on through the port 15 and into the compartment 19.

The stripper 18 includes a shaft 27 geared externally of the hopper to the drum shaft 23 and extending from the shaft 27 is a plurality, shown to be four, of blades 28 of somewhat stiff and yet slightly flexible leather. The stripper rotates counter-clockwise and the outer edges of its blades engage the ribbon of matted hair and bodily raises it off the drum so that very little, if any, of the hair which has so passed as a ribbon over the top of the drum is ever carried about the under side of the drum. After the ledges 25 pass the point 15 they begin to pick up the waste which accumulates in the bottom of the hopper and the pusher plate tends to pack the waste somewhat so that there is a fairly uniform density to the ribbon. The thin ribbon of hair floats away from the stripper and moves gently into the compartment 19 as indicated by the arrows. It is understood that at this point the hair while it is in ribbon form is still in an indefinitely matted condition and still has about the density of the original stock as it is fed into the hopper.

The device 12 comprises an upstanding metal casing 29 provided with a dividing wall 30 forming two compartments, the first or receiving compartment 19 and a second or discharging compartment 31. Communication is provided between the compartment by an aperture 32 about mid-height of the wall 30. Just below the aperture 32, roller 33 coats with a guide piece 34 to divide the compartment 19 into a lower receiving portion 35 and an upper discharging portion 36 and to form a constrictive throat 37 between the roller 33 and guide piece 34.

Journalled within the portion 35 and located one above the other are two picker rollers 38 and 39 intergeared exteriorly of the casing to rotate in the same direction, that is, counter-clockwise as indicated by the arrows. In the lower part of the upper portion 36 is journalled a single picker roller 40 intergeared to rotate counter-clockwise and thus in a direction to receive the material discharged through the throat 37 and advance the same with an undersweeping action through

the aperture 32 and hence into the compartment 31.

Within the compartment 31 are journalled three picker rollers 41, 42 and 43 intergeared with each other and with the main drive to rotate counter-clockwise. The several picker rollers act on the matted hair to disintegrate the same. They tear the hair particles apart, open up the mass, or differently expressed, reduce the specific density of the original stock until it assumes a light, fluffy cloud-like effect as it accumulates in the upper portion of the compartment 31.

In one practical operation and where a fine grade of fur hair was used, the hair particles were separated so that the mass might be said to be translucent when light was directed through a thickness thereof of about one foot. The fur material follows the path indicated by the arrows moving upwardly through the constricted throat 37 into the lower part of portion 36, then laterally through aperture 32 and then upwardly in the compartment 31.

The top wall 44 of the casing 29 is provided with a long, narrow slot 45 providing a discharge opening from the top of the compartment 31. It is particularly noted that there is no fan or other air pressure or blower means acting on the mass of hair as it moves through the casing 29 towards the discharge slot. The pickers and particularly the terminal pickers 41-43 are revolving at high speed and they may generate a gentle, barely perceptible updraft which assists in moving the disintegrated and flocculent mass of hair in a foam-like stream through the slot. The final discharge through the slot appears to be more of a pushing action of the advancing mass than a blowing action. The resulting fluff simply moves upwardly and thus against the action of gravity as would a foam from beer or other gas charged liquid. All that is visible is that a cloud of loose hair rises up out of the slot in a fairly uniform rate per unit of length along the entire length of the slot.

In those cases where the waste hair used is of the straight, non-curling type a peculiar phenomena takes place in the upper portion of the compartment 31 just below the slot. The final picker 43 exerts an orientating action on the mass to lay the hairs in the same direction. The hairs for the most part arrange themselves in parallelism with their original outer or pointed ends pointing in the direction of travel of the upper portion of the top picker roller 43, that is pointing to the left in the showing in Fig. 2. Of course, this means that the hairs so pointing have their thick end, base or root ends pointing to the right of the showing as they are lifted through the slot. While all of the hairs are not so orientated, and as a matter of fact all of them are not even brought into parallelism but remain intertwined with each other, still most of the hairs and particularly the long, thin fur hairs are so arranged with their pointed ends pointing in the same direction. The extremely short hairs in the mass have a tendency to remain in a more or less matted form but, of course, not so matted as in the original stock.

In those cases where a curling, screw-like or wavy type of fur hair is used, as in the case of sheep's wool, the hair is disintegrated and discharged through the slot as previously described, but in these cases there is no noticeable arrangement of the hair particles in parallel relation and no unidirectional pointing of the original outer ends of the hairs. This is presumably due to the

fact that in sheep's wool, for instance, the hair is interlocked by its screw or spiral construction and thus resists the action of the pickers to separate and arrange it in parallel relation.

The thread treating device 13 includes a set of drawing rollers 46 for drawing a single thread *t* under tension from a supply spool (not shown) and across the slot 45 in position to receive the discharge from the same. The slot is quite narrow and dimensioned so that the thread almost but not quite acts as a closure for the same as shown in Fig. 3. Differently expressed, the thread is centered over the slot and there is provided on opposite sides of the thread long clearances of extremely narrow width.

Considered from right to left of the showing in Figs. 1 and 2, there is disclosed a spring pressed presser foot 47 for restraining the freedom of movement of the thread under the pulling action of the rollers 46. It is suggested that in some cases the thread be coated with glue or other suitable adhesive and for this purpose there is shown an adhesive pot 48 mounted with the presser foot on a bracket 49 carried by the casing 29. The thread is passed over and in engagement with the flat top of a steel block 50 which acts to prevent the hairs from flying loose from the revolving thread. From the block 50 the covered yarn is passed through bore 51 of an ironer 52 mounted on top of the casing 29. The bore 51 is of conical form as shown in Fig. 4 with the larger end forming the intake end for receiving the coated thread or yarn.

The disclosure contemplates the twisting of the thread and resulting yarn about its own axis during the period while it is receiving the hair over the slot and while being drawn through the ironer. For this purpose, the yarn is passed through the bore 54 of rotary twister 55 including a tubular shell mounted for rotary movement about its own axis in a bearing 56 carried by bracket 57 in turn carried by casing 19.

Within the bore 54 are mounted four grooved spools 58 each free to turn about its own axis, two on each side of the thread. The spool axes 45 extend in parallel relation and transversely of the axis of rotation of the twister. The two middle spools are arranged so that their adjacent peripheries are each inset slightly beyond the path of the thread thereby to cause the thread as it passes through the bore to assume the wavy or undulated offset form shown in Fig. 2. Differently described, the plane tangent to the spools of one set is offset inwardly beyond the plane tangent to the spools of the other set. The twister is provided with a driving pulley 59 belted to the drive mechanism and intended to be driven at high speed. The twister acts on the yarn to give it a definite tortional twist and this twist extends from the presser foot 47 to the drawing rollers 46, the twist being clockwise between the twister and rollers and counterclockwise between the twister and presser foot.

During the movement of the twisted thread in its advance along the slot, it is dragged through the long narrow stream of loosely matted cloud of hair rising out of the slot and acts to pick up the hair. It is understood that as it passes through the mass of hair the thread is rapidly rotating so that the hair for the most part is twisted on to the thread to form a closely matted inner layer with many of the hairs sticking outwardly from the hair coating.

As the coated thread is advanced through the ironer 52 the more or less loose short hair coating

is circumferentially compacted; the hair more thoroughly intertwined and pressed firmly into the adhesive coating. The resulting yarn is of much less diameter than when fed into the ironer.

It is noted that the thread and subsequent yarn is advanced in the same direction, that is from right to left in the showing in Figs. 1 and 2, in which the straight hairs point as they were discharged through the slot. This means, of course, that most of the hairs are laid on the thread with their pointed ends in advance and due to the twist of the yarn as it passes through the ironer these hairs will be formed in the yarn with a screw-like or spiral lay and with their pointed ends in advance, that is, pointed to the left.

In this operation all of the hairs do not so lie within the outlines of the matted hair covering on the core forming thread. A certain percentage 20 of the threads, and usually the longer threads, having their inner, wider or base ends embedded in the adhesive and in the closely matted coating, but these pointed hair ends extend freely outwardly from the coating in somewhat spaced 25 apart relation along the entire length of the finished yarn.

The resulting yarn *y* is difficult to show pictorially due to the fineness of the hairs but reference to Figs. 5 and 6 will show the yarn at least in a crude way. In these figures the central core is formed by the twisted thread *t*, coated with a thin layer of adhesive *g* and into which adhesive the coating *c* of matted hairs is more or less embedded. The free outwardly pointing hairs are shown at *h*. By the time the yarn has reached the drawing rollers 46 it has passed along a stretch sufficient to insure an air drying and is delivered to the take up spool in a commercially dry condition. Incidentally, no more adhesive is used than is just sufficient to insure the sticking of the hair to the thread.

By means of a driving connection with a source of power the speed of the measuring drum 17 and pickers 38-43 is so synchronized with the travel of the thread *t* and resulting yarn *y* under the pull of the drawing rollers 46 that the requisite amount of fur covering is located on the thread per unit length to give the requisite extent of covering. For the purpose of controlling the relative speeds of the different drawing rollers, drum and picker rollers to meet the varying conditions imposed by different types of fur in use for the time being, the machine will include conventional change speed mechanism.

While this disclosure features the use of a single thread, and which in practice is a strong cotton thread, it is within the scope of the disclosure to use two threads parallel to each other and which threads become twisted one on the other conventionally. In this case, the adhesive may be omitted or materially reduced as the twisting of two threads one on the other is sufficient in most cases to hold the fur coating in place until it reaches the ironer. As the coated core, either of the single or double thread, passes through the ironer the coating will be rather firmly packed into place.

The finished yarn *y* formed is wound on to a take up spool 60 replaceably mounted on shaft 61 operatively connected to the drive mechanism. The spool 60 is used conventionally in a fabric weaving machine and the yarn thereon is woven into a cloth which on both sides looks very much like the fur side of a natural fur skin. It partakes of the appearance of the hair of the animal

which supplied the waste cuttings. For instance, waste hair from a gray squirrel can be made into a yarn, the yarn into a fabric and the fabric into an artificial gray squirrel coat which looks as if it were made from natural gray squirrel skins. Fabrics made from the waste hair cuttings from a long haired animal like a fox produce a beautiful black or brown soft glossy surface which with its fine hair ends produces the silky effect of a high price skin of fox.

By suitably mixing in the hopper the waste hair from different kinds of fur an indefinite number of differently appearing forms of resulting fabric may be obtained.

While fur hair of both the straight and curled variety has been specifically described herein, it is within the scope of the disclosure to use other forms of waste material such, for instance, as feathers.

We claim:

1. In the art of forming a fur covered yarn, the method which consists in drawing from an indefinite matted mass of fur waste hairs a thin layer of the same in measured amounts per unit of time, discharging the layer into a confined space; progressively disintegrating the material so discharged to separate the same into a fine floating fluff, causing the fluff at the end of the disintegrating step to move gently upwardly and thus against the action of gravity and into a narrow, long path and causing an adhesively coated thread to traverse along the length of said path and closely above the same to pick up the fur fluff as it rises on to the thread, the travel of the thread and the amount of fur waste advanced in the layer per unit of time being synchronized to provide the requisite degree of fur coating on the thread per unit of length.

2. In the art of forming a fur covered yarn, the method which consists in drawing from an indefinite matted mass of fur waste hairs a thin layer of the same in measured amounts per unit of time, discharging the layer into a confined space, progressively disintegrating the material so discharged to separate the same into a fine floating fluff, causing the fluff at the end of the disintegrating step to move gently upwardly and thus against the action of gravity and into a narrow, long path and causing an adhesively coated thread to traverse along the length of said path and closely above the same to pick up the fur fluff as it rises on to the thread, while twisting the thread about its own axis as it passes along said path.

3. In the art of preparing from an indefinite matted mass of waste fur hairs a fur coating for a yarn, the method which consists in forming a thin layer from the original matted mass, discharging the layer as formed into a confined space free of any fan or other air pressure or blower action, subjecting the same while in said space to a distintegrating action to reduce the original density to a light fluffy mass and causing the final mass to float from its point of disintegration to its point of discharge in substantially quiescent air upwardly and thus contra to the action of gravity as it is discharged from said confined space directly into the atmosphere and substantially without assistance from any kinetic force inherent in the air in said space.

4. In the art of forming a filling for a yarn, the method which consists in withdrawing from a mass of matted fur hairs a limited amount of the same per unit of time in the forming of a thin ribbon, subjecting the same to successive

5. picking actions to disintegrate the material of the ribbon progressively to form the same finally into a light fluffy mass and with the hair particles sufficiently separated so that the mass is translucent and gently lifting, in distinction from blowing or throwing or hurling, the same gently and while causing it to assume a unilateral dimension as it is caused to be transferred on to a thread passed therethrough and along the path defined by said unilateral direction.

10. 5. In the art of forming a filling for a yarn, the method which consists in withdrawing from a mass of matted fur hairs a limited amount of the same per unit of time in the forming of a thin ribbon, subjecting the same while exposed to the environmental air condition to successive picking actions to disintegrate the material of the ribbon progressively to form the same finally into a light fluffy mass and with the hair particles more or less adhering to an extremely loose matted form but sufficiently separated so that the mass is translucent and causing the mass while in such translucent form to assume a lengthwise form and causing the mass to be moved by the pushing action of the advancing mass and causing the translucent mass to rise upwardly direct from the last picking step to a discharge point while maintaining its translucent condition.

15. 6. In the art of treating a matted mass of straight fur hair, the method which consists in subjecting the mass to a picking action to disintegrate the mass and to cause the hairs for the most part to assume a substantially parallel relation, and subjecting the resulting hair to the effect of a lifting pressure while carrying the mass of carded hair to assume a unilateral form extending in the direction in which the hairs for the most part lie at the termination of the picking action.

20. 7. In the art of treating a matted mass of straight fur hair, the method which consists in subjecting the mass to a picking action to disintegrate the mass and to cause the hairs for the most part to assume a substantially parallel relation and causing those hairs which are in such parallel relation to pass upwardly through a narrow slot extending in the direction of such parallel relation.

25. 8. In the art of filling yarn the method which consists in drawing a thread through a mass of fur hairs where the hairs extend for the most part in the direction of the length of the thread while twisting the thread and subjecting the thread with its layer of hairs thereon to an ironing action, said ironing action progressively drawing the yarn radially inwardly, thus causing the hair to become condensed and matted circumferentially about the twisting thread.

30. 9. The method of producing from a matted mass of fur hairs a thin flat ribbon of the same, and separating its hairs into a fluffy mass causing the fluffy mass to assume a unilateral form and applying said fluffy mass to a travelling thread when the thread and unilateral mass are in parallel relation.

35. 10. The method of feeding yarn filling materially upwardly in a long narrow sheet, drawing a yarn thread across said sheet in position to pick up the filling, ironing the filling on to the thread, while rotating the resulting yarn.

40. 11. The method of drawing yarn under tension first through an ironer to compact and reduce the diameter of the yarn and then through 75 a twister to twist the yarn about its own axis

and thus give it a tortional twist as the yarn is drawn through the ironer.

12. In the art of forming a fur covered yarn, the method which consists in drawing from an indefinite matted mass of fur waste hairs a thin layer of the same in measured amounts per unit of time, discharging the layer into a confined space, disintegrating the material so discharged to separate the same into a fine floating fluff, causing the fluff at the end of the disintegrating step to move gently into a narrow, long path and causing an adhesively coated thread to traverse along the length of said path to pick up the fur fluff as it moves on to the thread, the travel of the thread and the amount of fur waste advanced in the layer per unit of time being synchronized to provide the requisite degree of fur coating on the thread per unit of length.

13. In the art of forming a fur covered yarn, the method which consists in drawing from an indefinite matted mass of fur waste hairs a thin layer of the same in measured amounts per unit of time, discharging the layer into a confined space, progressively disintegrating the material so discharged to separate the same into a fine floating fluff, causing the fluff at the end of the disintegrating step to move gently into a narrow, long path and causing an adhesively coated thread to traverse along the length of said path and closely adjacent to the same to pick up the fur fluff as it advances on to the thread, while twisting the thread about its own axis as it passes along said path.

14. In the art of forming a filled yarn, the method which consists in drawing from a mass of filling material a layer of the same, disintegrating the layer to separate the same into a loose mass of fine floating fluff with its particles substantially separated, causing the fluff to assume a layer of relatively small thickness and disposed

in a fixed plane, and directing the fluff while in said plane on to a thread travelling in said plane and thus through the layer of small thickness of fluff while twisting the thread.

15. In the art of forming a fur filled yarn, the method which consists in forming in space a thin layer of fur hair fluff disposed in a plane, passing an adhesively coated thread under tension through said fluff while in such plane to cause the thread to pick up particles of the fluff and twisting the thread in one clockwise direction while passing along the place where the thread picks up the fluff.

16. The method of claim 15 and wherein the thread is twisted in the opposite direction after it has passed said place thereby tending to release the tension on the thread after the fluff has been applied thereto.

17. The method of claim 15 and in which the resulting yarn is ironed to circumferentially compact the hair into the adhesive coating.

18. In the art of forming a fur filled yarn with a closely matted inner layer, which consists in causing an originally more or less matted mass of fur hairs to assume the form of a light fluffy mass with at least some of the hair orientated into parallel relation with their pointed ends pointed in the same direction, advancing the mass by a pushing action of the advancing mass in distinction from a blowing action on to a thread under tension and travelling in the direction in which the pointed ends of the hairs point and twisting the thread in one rotary direction as it advances across the place where it receives the hairs and twisting the resulting filled yarn in the opposite rotary direction immediately after it has passed said space.
